GARMENT AND METHOD OF MAKING
THE SAMEAlbert George Neel, Nazareth, Pa., assignor to
Nazareth Mills, Incorporated, Nazareth, Pa., a
corporation of Pennsylvania

Application March 13, 1946, Serial No. 654,020

11 Claims. (Cl. 2—111)

1

My invention is a garment, and a method of making a garment, having shoulders comprising layers of fabric forming straps and flaps having free inner edges permitting the expansion of the neck opening between the shoulders for the passage of the head of a wearer and the automatic constriction of such neck opening by pulling the body of the garment in place to bring the sides of the neck opening into desired relationship to the sides of the neck of the wearer.

Leading objects of my invention are to obviate the waste of fabric involved in cutting shoulder strap extensions of abnormal length to provide usual flaps or anchorages extending over the shoulders and overlapping front and back shoulder straps, and to obviate or minimize raw edges around upper portions of the armholes of the garment body. This avoidance of raw edges along the upper portions of the armholes makes my invention particularly applicable to the construction of sleeveless garments, but also provides a firm edge for the attachment of sleeves when sleeved garments are made in accordance with my invention.

My invention involves the retention of integral fabric sections which are normally excised to form armholes to provide flaps along portions of the armhole edges of the garment body. Such retained sections are folded laterally of the garment along the lines of the armhole edges. This doubling back of the retained sections provides hem-like margins for portions of the armholes, and also provides flaps integral with the garment body and each of which overlies one of a complementary pair of shoulder straps and is attached to and anchors the other shoulder strap of that pair.

The upper edges of the shoulder straps forming parts of the garment front are preferably seamed to the upper edges of the integral flaps laterally inturned from armhole edges of the garment back and lying between the back and front of the garment, and the upper edges of the shoulder straps forming parts of the garment back are preferably seamed to the upper edges of the integral flaps inturned laterally from the edges of the armholes of the garment front and overlying such front.

The inner lateral edges of the respective flaps are unconfined but the lower portions at least of the pair of front flaps preferably are curved divergently outward, and the lower portions at least of the pair of back flaps are also preferably curved divergently outward. The free

2

edges of the front flaps form continuations of the edge of the neck recess in the garment back, and the free edges of the back flaps form continuations of the edge of the neck recess in the garment front. The neck opening of the garment formed by such recesses may be expanded to substantially the full width of the garment between the tops of the armholes by the relative movements of the straps and flaps and downward stress on the body of the garment tends to restore the flaps and shoulder straps to their normal overlapped positions.

The fabric forming the garment may be shaped in any desired manner to form neck recesses, armholes, shoulder straps and flaps in accordance with my invention. In making undergarments, it is generally preferable to use tubular knitted fabric having longitudinally extending wales. Such fabric may be cut normally to its side edges into sections equal to the desired lengths of two garments, and such double lengths may be severed diagonally to form a pair of garment blanks each having the front forming section shorter than the back forming section. Each blank may have sections excised from the corners formed by the intersection of its normal edge with the side edges to provide front and back neck forming recesses in the usual manner.

30. In accordance with my invention, each flattened blank is cut longitudinally or walewise intermediate the neck forming recesses and along lines which, at a short distance below the normal or top edge, begin to diverge toward the side edges. The lower parts of such diverging cuts are intersected by cuts along lines converging toward the center of the flattened blank. The diverging, and preferably convex, cuts and the converging, and preferably concave, cuts excise segments from both layers or laps of the flattened tubular fabric to form openings therein, but leave integral flaps projecting toward but severed from one another and extending laterally into the area lying between the maximum width of such openings and the top edge of the blank. If desired, the upper portions of such flaps may be severed by slits from the fabric sections designed to constitute shoulder straps and lying adjacent to the neck recesses.

40. A blank so shaped by cutting is shifted circumferentially and refattened so that the sections forming the original side edge bends extend longitudinally in the center of the front and back of the garment blank, and the new side

50

55

edges formed by refattening intersect the points of convergence of the downwardly converging cuts above described. The edges formed by these downwardly converging cuts now form the lower edges of the armholes in the front and back of the garment, and the edges formed by the downwardly diverging cuts above described now provide free edges of integral flaps projecting laterally from the shoulder straps of the front and back. These flaps may be now doubled back along the armhole edges, and the upper edges of all or some of them are permanently or detachably connected with the upper edges of shoulder straps as above described.

The principles and characteristics of my invention and the manner and process of making, constructing and using my improved garment will further appear from the accompanying drawings and the following explanation of the best mode in which I have contemplated applying such principles.

In the drawings, Fig. 1 is a front view of a child's waist or undershirt embodying my invention; Fig. 2 is a back view of the garment shown in Fig. 1 with the parts broken away; Fig. 3 is a plan view of a pattern for guiding the cutting of a flattened tubular fabric to form a garment blank in accordance with my invention; Fig. 4 is a plan view of the blank cut according to the pattern of Fig. 3 after the original edge folds of the blank have been shifted 90° circumferentially of the blank, and the blank refattened; Fig. 5 is a plan view of a pattern for guiding the cutting of a sleeve blank from folded fabric; Fig. 6 is a plan view of an unfolded sleeve blank cut according to the pattern of Fig. 5; Fig. 7 is a fragmentary front view of the upper portion of the blank shown in Fig. 4 with the top edges of the front shoulder straps attached to the top edges of flaps turned inward along the armhole edges of the back; Fig. 8 is a fragmentary somewhat diagrammatic perspective view illustrating the joinder of the top edge of one of the front shoulder straps to the top edge of a flap turned inwardly from an armhole edge of the back, as shown in Fig. 7; Fig. 9 is a front view of the upper portion of the partly assembled garment shown in Figs. 7 and 8 after the top edges of the back shoulder straps have been connected with the top edges of flaps turned inwardly along armhole edges of the front; Fig. 10 is a fragmentary somewhat diagrammatic perspective view showing the attachment of the tops of the back and front shoulder straps to the top edges of the flaps inturned along the armhole edges of the front and back, as shown in Fig. 9; and Fig. 11 is a front view of the garment shown in Fig. 9 with a complementary pair of folded sleeve blanks similar to that shown in Fig. 6 positioned for attachment thereto along the fold lines of the inturned flaps and the armhole edge sections below such flaps.

Garment bodies embodying my invention are preferably made from knitted tubular fabric having longitudinally extending wales. The width of the tubular fabric when flattened preferably approximates the desired width of the finished garment.

In accordance with my invention, the front and back of a garment body are shaped to form neck recesses and armholes with flaps projecting laterally from edges thereof, as indicated in Fig. 4. Such shaping may be conveniently effected by

superposing flattened tubular strips of fabric and simultaneously cutting the stacked strips in accordance with a pattern, such as shown in Fig. 3, which is laid longitudinally or walewise along the top of the stacked series of flattened tubular fabrics.

The pattern, and the blanks as cut in accordance therewith from the tubular fabric as initially flattened, preferably has substantially parallel side edges 1 and 2, a bottom edge 3, which may be of any desired contour, and a top edge 4, which is substantially normal to the side edges 1 and 2. The upper corners of the pattern and of the garment blank are cut on arcuate lines 5 and 6, which may be of equal or unequal length or contour. Slits 7 and 8 may be cut normal to the edge 4 at suitable distances from the inner extremities of the lines 5 and 6 to better define the width of shoulder strap sections which lie between the arm holes and the planes of the neck recesses of the garment. The pattern and the garment blank are slit longitudinally by cuts along the line 9 approximately midway between the slits 7 and 8. The cut along the line 9 is of approximately the length of the slits 7 and 8 and below such point the pattern and blank are cut along diverging and preferably convexly arcuate lines 10 and 11. The lower extremities of the cuts along the lines 10 and 11 are intersected by cuts along downwardly converging and preferably concavely arcuate lines 12 and 13 which come together at their lower extremities. The upper portions of the cut along the lines 12 and 13 may extend slightly beyond the bottom termini of the cuts along the lines 10 and 11 and lie approximately in alignment with the cuts along the lines 7 and 8. The cuts along the lines 10, 11, 12 and 13 remove segments from the central portions of both layers of the flattened tube and leave therein centrally disposed openings having opposite concave lower edges and opposite convex upper edges.

In constructing a garment, the tubular fabric blank is turned 90° circumferentially about a longitudinal axis so that the sections forming the folds along the edges 1 and 2 are positioned medially and extend longitudinally of the tube when refattened as shown in Fig. 4.

The cuts along the line 5 produce a neck recess 5a in the front 1a of the garment, and the cuts along the line 6 produce a neck recess 6a in the back 2a of the garment.

The openings formed in each fabric layer by the cuts along the lines 9, 10, 11, 12, 13 now form armholes in the upper part of the garment and at the side edges thereof.

The cuts along the line 12 form concave outer edges 12a of the lower parts of the armholes in the front 1a, and the cuts along the line 13 form the concave outer edges 13a of the lower parts of the armholes in the back 2a. The slits along the line 7 form outer edges 7a for shoulder strap sections 1b of the front of the garment, and the slits along the line 8 form outer edges 8a for the shoulder strap sections 2b of the back of the garment. The cuts along the lines 9 and 10 form outer edges 10a of flaps 14 which project laterally of the front 1a of the garment beyond an imaginary line joining the proximate extremities of the edges 7a and 12a. The cuts along the lines 9 and 11 form outer edges 11a of flaps 15 which project laterally of the back 2a of the garment beyond an imaginary line joining the proximate extremities of the edges 8a and 13a.

As shown in Figs. 7 and 8, the top edges of the shoulder straps 1b are connected, as by abutted

or lapped seams, to the top edges of the flaps 14 after the latter have been folded inward between the front 1a and back 2a along the imaginary lines connecting the extremities of the edges 8a and 13a as shown in Fig. 8.

The flaps 14 are then folded over the front 1a along imaginary lines connecting the proximate extremities of the edges 7a and 12a, and the top edges of the inturned flaps 14 are then seamed to the top edges of the shoulder straps 2b, as shown in Figs. 9 and 10.

If the garment is to be used as a sleeveless garment, such for instance as an under-vest or infant's band, the edges of the neck, armholes and bottom may be finished in any suitable manner, as, for instance, by overstitching. The portion of the edge of the armhole formed by the folds of the flaps 14 and 15 may be finished by overstitching or left without overstitching since the doubling back of the flaps gives the effect of a hemmed margin, which does not ravel and which is amply strong to withstand the stresses imparted thereto by the movements of the wearer.

The flaps 14 and 15 are not attached along their edges 10a and 11a to the back and front of the garment, and the edges 10a form in effect continuations of the edge of neck recess 6a, and the edges 11a form in effect continuations of the edge of the neck recess 5a. Consequently the neck opening can be stretched open practically the full width of the garment to facilitate the movement of the garment over the head of the wearer. When positioned on a wearer, the weight of the garment, or the stress of other garments attached thereto, tends to draw the flaps into the positions shown in Figs. 9 and 11 and the shoulder straps 1b and 2b into juxtaposition to the base of the neck of the wearer, particularly at or adjacent to the seams extending transversely to the garment by which the shoulder straps are secured to the flaps.

When it is desired to provide a garment made in accordance with my invention with sleeves, as shown in Figs. 1 and 2, a sleeve pattern 16, shown in Fig. 5, is laid over folded fabric and the latter is cut to produce complementary pairs of sleeve blanks 16a, one of which is shown in Fig. 6. The blanks 16a so formed then have their edge 17 seamed to the body along the folded edges of the flaps 14 and 15, their edges 18 seamed to the respective edges 12a and 13a, and their edges 19 seamed to one another to produce the garment shown in Figs. 1 and 2. The wales of the sleeves extend transversely to the wales of the flaps. Each edge 20 of the blanks 16a may be finished in any desired manner, such as by overstitching, to form a cuff.

It will be noted that the folding of the front flaps over the front 1a brings into view a surface of the fabric opposite to that shown in the adjacent body portions of the garment, and, if desired, the exposed surfaces of the flaps may be made to contrast to the remainder of the garment to any desired degree or may be made to conform therewith.

Having described my invention, I claim:

1. A body garment having front and back sections and containing an armhole, one of said sections having an integral flap folded along an edge of said armhole and overlapping said section, said flap having an edge transverse to its fold line and connected with the other of said sections along an edge thereof extending transversely of the garment adjacent to the shoulder thereof, said

flap being free, inwardly from its fold line, from the section over which it is overlapped.

2. A body garment having front and back sections and containing an armhole, one of said sections having an integral flap folded along an edge of said armhole and having a free edge overlapping said section, said flap being free, inwardly from its fold line, from the section over which it is overlapped, the other of said sections and said flap having complementary edges of approximately equal widths, connected together along a line extending transversely of the garment and adjacent to the shoulder thereof.

3. A body garment having front and back sections and containing an armhole, each of said sections having integral flaps folded along opposite edges of said armhole, each flap overlapping the section integral therewith, the flap integral with the front section having an edge transverse to its fold line connected with the back section only along an edge thereof extending transversely of the garment adjacent to the shoulder thereof, and the flap integral with the back section having an edge transverse to its fold line and connected with the front section only along an edge thereof extending transversely of the garment adjacent to the shoulder thereof.

4. A body garment having front and back sections and containing armholes, said sections each having a pair of flaps integral therewith and folded along edges of the respective armholes, each flap overlapping the section integral therewith, the flaps integral with the front section having edges transverse to their fold lines and connected with edges of the back section along lines extending transversely of the garment and adjacent to the shoulder lines thereof, and the flaps integral with the back section having edges transverse to their fold lines and connected with edges of the front section along lines extending transversely of the garment adjacent to the shoulder lines thereof, said flaps being free relatively to the sections they overlap excepting along their fold lines.

5. A body garment having front and back sections and containing armholes, said sections each having integral flaps folded in overlapping relation to the respective sections, the fold lines of said flaps delimiting the upper portions of edges of said armholes, each of said flaps having an edge extending transversely to its fold line and said front and back sections each having edges extending transversely of the garment and connected with said edges of the flaps integral with the other section.

6. A body garment having front and back sections and containing an armhole, and a sleeve, said sections each having an integral flap folded along an edge of said armhole and connected with one another, said flap folded from the front section being connected with the shoulder portion of the back section only and the flap folded from the back section being connected with the shoulder portion of the front section only, and said sleeve being seamed to said garment along the fold lines between said flaps and sections.

7. A blank for a body garment comprising a flattened tubular body having recesses along its edges, said body having armhole forming flaps projecting laterally from the edges of said body between said recesses and an end of the blank and adapted to be folded over said body along lines forming continuations of edges of said recesses to form armholes.

8. In a method of forming a garment blank by

cutting a strip of flattened tubular fabric having side edges and an end edge substantially normal to said edges, the step which comprises forming armholes by cutting the fabric intermediate its side edges along lines which diverge downwardly and outwardly from a point adjacent to said end edge toward said side edges and along lines which converge downwardly and inwardly from said lines first named, said cuts forming flaps bordering the armholes and an armhole opening between and at the ends of such flaps.

9. In a method of forming a garment blank by cutting a strip of fabric having longitudinal edges, the step which comprises cutting the fabric intermediate its longitudinal edges along lines which diverge longitudinally toward such edges and along lines which converge longitudinally and inwardly away from said edges, said cuts forming flaps and an opening between and at the ends of such flaps, said flaps together having a maximum width substantially equal to the maximum width of said opening.

10. In a method of forming a garment, the steps which include forming a blank having a front and a back each provided with a shoulder strap and an integral flap projecting laterally

from an edge of its shoulder strap, attaching the top edge of the front shoulder strap to the top edge of the back flap only, and attaching the top edge of the back shoulder strap to the top edge of the front flap only.

11. In a method of forming a garment, the steps which include forming a blank having a front and a back each provided with a shoulder strap and an integral flap extending laterally
 10 from an edge of its shoulder strap, turning the back flap inwardly between the front and the back and securing its top edge to the front shoulder strap and folding the front flap over the front and securing its top edge to the back shoulder strap.

ALBERT GEORGE NEEL.
